RAILROAD TRACK GAUGE, LEVEL, AND
ALIGNING TOOL

Paul F. Fischer, Streeter, N. Dak., assignor of one-third to Franklin H. Jahnke, Alfred, N. Dak., and one-third to Oscar Olson, Streeter, N. Dak.

Application August 26, 1938, Serial No. 227,005

2 Claims. (Cl. 33—145)

My invention relates generally to means for use by a railroad roadmaster in checking the spread, the level and the alignment of track, and particularly to a combined track gauge, level, and alignment tool, and an important object of my invention is to provide a tool of this character which is very compact and easily portable when in a collapsed condition, and which greatly facilitates the maintenance and laying of track.

Other important objects and advantages of my invention will be apparent from a reading of the following description taken in connection with the drawings, wherein for purposes of illustration I have set forth a preferred embodiment of my invention.

In the drawings:

Figure 1 is a general side elevational view of the tool showing the same in extended or open position.

Figure 2 is an enlarged fragmentary top plan view of Figure 1.

Figure 3 is an enlarged fragmentary bottom plan view of a portion of Figure 1.

Figure 4 is a vertical longitudinal sectional view taken through Figure 1 approximately on the line 4—4 of Figure 1 and looking downwardly in the direction of the arrows.

Figure 5 is an enlarged transverse vertical sectional view taken through Figure 1 approximately on the line 5—5 of Figure 1 and looking toward the left in the direction of the arrow.

Figure 6 is a longitudinal vertical sectional view taken through Figure 2 approximately on the line 6—6.

Figure 7 is a bottom plan view of the insulated block.

Referring in detail to the drawings, the numeral 5 generally designates the tool which is composed of the elongated generally rectangular section 6 and the generally rectangular elongated section 7, the inner and abutting ends of the sections being connected by a hinge 8 at what is normally the bottom of the tool, so that the sections may be folded together to make the tool compact for carrying and storage purposes, and while the tool is in use as an aligning tool, in which operation the section 6 alone is necessarily used.

On left hand outer end of section 6 is an insulated block 9 (Fig. 7) which is attached thereto by means of a screw 10 and this insulated block has an oval opening 11 to enable operator of instrument to determine whether contact portions 12 and 13 are both against the rail so that main part of 6 and 7 rests across rails exactly at right angles to the rails when gauging or aligning track. The bottom part of insulated block 9 (as shown in Figure 1) is of such dimensions as to permit it to drop down between main rail and guard rails and in frogs at switches

when gauging track where guard rails are used and at switches. The generally rectangular cross section of the block 9 is indicated in Figure 1 of the drawings. At a distance exactly 28 $\frac{1}{4}$ inches from the contact points 12 and 13 is a pivot 5 mounting 14 on which turns a collar 15 into which is threaded as indicated by the numeral 16 one end of a removable and interchangeable pin 17 which when not in use assumes the longitudinal position illustrated in Figures 1 and 2 of the drawings and can be used in either an upwardly projecting position or a downwardly projecting position at an angle of ninety degrees with respect to the longitudinal axis of the tool, the mounting pin 14 being arranged in connection with a bracket 18 fastened to the side of the section 6 and having an upper cut-out 19 and a lower cut-out 20 to receive the side of the pin to hold the same in alignment when the pin is in an upwardly projecting position and in a downwardly projecting position, respectively.

On a side of the section 6 adjacent the location of the pin 17 is the slide plate 21 which is mounted by respective bolts or screws 22, 23 which are fastened in the top of the section 6 25 and pass through slots 24, 25 in the plate 21. A handle 26 is provided on the left hand end of the slide to enable manipulating the slide across the joint between the sections 6 and 7 when the sections are in opened or aligned position; and under the retainer plate 27 which has a portion 28 bolted as indicated by the numeral 29 to the top of the section 7 and has an upset portion 30 under which the slide 21 fits, the upset section being equipped with a thumb screw or wing nut 31 which is adapted to be turned down to bear on the top of the plate 21 to lock the same in place and to hold the sections 6 and 7 positively aligned in their extended open positions.

Referring now to the section 7 the same has 40 on top and bottom respective bubble levels 32, 33 either of which may be brought into service according to the position of the tool. Adjacent the outer end of the section 7 is a vertical slot in which is adjustable a rule 34 which is adapted to be held in adjusted position by a set screw 35 and which traverses the opposite wall 36 of the section 7 as shown in Figure 4 and engages against the adjacent side of the rule 34.

Slidably telescoped on the section 7 at a point 50 inward of the rule 34 is the slide which is generally designated 37 and which is traversed by a clamping bolt 38 which passes also through slots 39 and 40 in the opposite sides of the section 7, the bolt 38 being provided with a 55 wing nut 41 for clamping purposes. The slide 37 is adjustable along the section 7 in conjunction with graduations 42 which indicate the track spread.

By referring to Figure 5 of the drawings the 60

specific construction of the mounting for the pin 17 may be understood as comprising the already mentioned bracket 18 which has a bushing 43 which extends into a tubular part 44 in the 5 wall of the section 6 and threads therein, with the bolt 14 passing beyond the bushing and having a head 45 between which and the bushing is an expanding spring 46 whose purpose is to pull the bolt 14 in a right hand direction as 10 viewed in Figure 5 when the pointer or pin 17 has been pulled out and then is brought into alignment with one of the openings 19 and 20, in effecting an operative adjustment of the pin.

In employing the device of the invention in 15 ordinary track gauging operations, the same is taken off the car or other supporting means and the sections brought into alignment and then the slide 21 is pushed into position and locked by means of the set screw 31. For leveling or determining whether the track is level, the bubble level 20 32 or 33 is employed. If when the instrument is laid on the tops of the rails the bubble level is off center, the rule 34 in the slot 33 is brought into use. The rule equipped end of the device is raised 25 until the level bead is in the level position, the movement being made relative to the rule 34, so that the amount of movement relative to the starting point on the rule 34 can be readily determined to show exactly how high or low the 30 rail is at the point gauged. If desired the instrument can be turned up-side-down and the level 33 can be used instead of the level 32.

To gauge the amount of rail spread the device is laid upon the rails so that the insulated 35 block 9 rests on one of the rails and the points 12, 13 or one of them snugly engage the inside of the rail. Then by adjusting the slide 37 on the opposite end of the device relative to the graduations 42 it can be quickly determined how much 40 the rails are spread. The slide 37 may, if desired, be set at 56½ inches by moving the same to the proper graduation and turning down the thumb screw nut 41, and then the track can be gauged from rail to rail. The graduations 42 conveniently run from 56 to 57¾ inches.

The block 9 is made of insulating material to 45 eliminate any possibility of shorting circuits in automatic block territory. In view of this provision, there is no possible chance of putting a block signal into operation as a result of dropping the device across the rails. The block 9 is so constructed that the track can be gauged or leveled 50 where guard rails are in use and can be used at frogs and switches, since it is of such shape and dimensions as will permit it to drop down between 55 the main rail and the guard rail.

When the device of the invention is used for aligning tracks, it is used either folded up in a compact portable form or extended as it is in 60 track leveling operations. This makes the device available for construction crews and other maintenance crews in laying new tracks or re-aligning tracks.

To use the instrument for aligning tracks when 65 the instrument is opened up as a track level or track gauge, the pin 17 is turned so that it points downwardly. The mounting 14 is so located that when the pin 17 points downwardly the point of the pin 17 is exactly 28¼ inches from the terminals 12, 13 on the block 9. 56½ inches being the center gauge, the distance 28¼ inches from the terminals of the block 9 is exactly the center of the track. The center of the track is generally surveyed and staked out by civil engineers

and a tack is driven in the stake exactly where the center of the track should be. By resting the insulating block on the rails so that the terminals 12 and 13 are up against the inside of the rail, the rail can be moved in toward the middle of the 5 track until the pin 17 indicates where the rail should be spiked by pointing directly to the tack on the stakes as placed by the engineers. This aligning operation can be done with the instrument in an open or closed position by simply 10 changing the direction of projection of the pin 17 so that it points upwardly. As a matter of fact it would be seldom necessary to have the instrument in the open position when aligning track, since there never is more than one rail laid at a 15 time and it is not necessary to open up the instrument to align this rail or track. Incidentally the pin 17 can be entirely removed when not in use by screwing the same out of the collar 15 so as to thereby eliminate any possibility of the pin 20 injuring a workman. The pin 17 can be of different lengths depending on the requirements of the particular railroad or roadbed and the size of the rails being used.

Although I have shown and described herein 25 a preferred embodiment of my invention, it is to be definitely understood that I do not desire to limit the application of the invention thereto, and any change or changes may be made in the materials and in the structure and arrangement 30 of the parts, within the spirit of the invention and the scope of the subjoined claims.

Having described the invention, what is claimed as new is:

1. A roadmaster's tool comprising a bar, rail 35 engaging blocks on opposite ends of the bar, a pointer swingably mounted intermediate the ends of said bar, said pointer being pivoted on a horizontal axis to swing from a position in alignment with said bar to a depending operative position, a pivot traversing a portion of said bar and being longitudinally slidable on its axis relative to the bar and on which said pointer swings, said pointer being formed with a projection and said bar being formed with horizontal and vertical recesses, and spring means acting between 40 said bar and said pivot for resisting longitudinal movement of said pivot so as to retain said projection on the pointer seated in either the horizontal or the vertical recess.

2. A roadmaster's tool comprising a bar having rail engaging blocks on its opposite ends, a pointer swingably mounted between the ends of said bar to lie along said bar or to depend therefrom, said bar having a vertical longitudinal wall 55 laterally spaced from another part of the bar, said wall being formed with an opening, a tubular bushing secured in said opening and having a head engaging the laterally outward face of said wall, said head being formed in its laterally outward side with a first groove extending parallel to the length of the bar and a second groove arranged at a divergent angle relative to the first groove, a pivot slidable in the bore of said bushing and having a boss on its laterally inward end, 60 spring means operating between the bushing and said boss for urging said pivot in a laterally inward direction, and a pointer rod pivotally secured on the laterally outward end of said pivot, said pivot rod being formed with a lateral projection 65 designed to engage in either of said grooves for holding the pointer aligned with the bar or depending therefrom.

PAUL F. FISCHER.
